WALTER SCOTT, OF PLAINFIELD, NEW JERSEY; ISABELLA SCOTT AND DAVID JOHN SCOTT EXECUTORS OF SAID WALTER SCOTT, DECEASED.

MULTICOUPLE MULTIREVOLUTION PRINTING-MACHINE.

1,040,783.

Specification of Letters Patent. Patented Oct. 8, 1912.

Application filed November 17, 1905. Serial No. 287,863.

To all whom it may concern:

Be it known that I, WALTER SCOTT, a citizen of the United States of America, and a resident of Plainfield, Union county, New Jersey, have invented certain new and useful Improvements in Multicouple Multirevolution Printing-Machines, of which the following is a specification.

The present invention relates generally to printing machines, and has more particularly reference to the arrangement and construction of the parts of a multi-couple multi-revolution machine, and to tripping mechanism connected therewith.

In the prior art of multi-revolution machines, it has been customary to provide means for automatically tripping and untripping the impression at regular intervals once to a certain number of revolutions or once to each cycle of the printing couple. Means have further been provided for preventing the form and impression members composing the printing couple from returning into contact by rendering the automatic means aforesaid inoperative or incapable of acting to bring the separated members into contact.

The automatic means which act at regular intervals to trip and untrip the impression are for the purpose of preventing the form from placing the ink on the packing of the impression cylinder during that revolution of the impression cylinder when there is no sheet to receive the impression, and to bring the form and impression members properly into contact when an impression is to take place. It sometimes happens, however, that a sheet is missed in feeding, and to prevent the form from coming in contact with the impression cylinder during its first revolution, the means, for rendering the automatic means aforesaid incapable of returning the members of the printing couple into contact, are provided. Likewise, when a sheet is not fed properly and the impression would be placed out of register with the sheet, it is desirable to prevent the impression and thus save the sheet which would otherwise be spoiled. Again, when inking up the form, it is of course necessary to run the machine with the impression tripped.

The aforesaid means for rendering the automatic means inoperative are generally under the control of the operator, but in case automatic feeders are used, it is customary to connect up the tripping mechanism and feeding machine either mechanically as by springs or weights, or electrically. This is so well understood in the art, that no need exists for going into details relative thereto.

In the art relating to multi-revolution machines, especially of a rotary nature, there has been developed a type of machine in which a plurality of printing couples are employed to print on the same side of the sheet for multi-color work or the like. Obviously, this advance in the art makes it desirable to produce a machine in which the impression of the several couples is tripped and untripped automatically and periodically at regular intervals, combined with means, set in motion by an actuating device under the control of the operator or of an automatic feeding machine, for preventing the automatic means from bringing the members of the several couples into printing contact. These means should act sequentially upon the several printing couples, so that the second printing couple will not be held out of impression until the sheet, properly printed by the first couple, has been printed on the second couple, and so on, and whereby also when the automatic means regain control of the machine, the members on the said second printing couple will not be brought into contact until the sheet printed properly by the first printing couple is received by the impression cylinder of the said second printing couple.

The main object of the present invention is therefore to produce a plurality of printing couples adapted to print on the same side of the sheet, in combination with means for automatically and periodically, at regular intervals, tripping and untripping the impression of the members composing the several couples, together with means, under the control of the operator or of the automatic feeder, for maintaining the members in their separated position, the said means being operable from a single actuating de-

vice to communicate the motion to the members of all the couples in regular sequence, and whereby when the said actuating device is released, the machine will resume its former operation and be tripped and untripped again automatically at regular intervals.

The form and impression members comprising the printing couple will preferably be of the rotary type and are so shown in the drawings forming a part of this specification, though I do not wish to limit myself for all purposes to a construction involving rotary printing couples.

Another object resides in including the above-mentioned printing couples and tripping mechanism in a unitary structure.

Still another object resides in providing sheet conveying means such as transfer cylinders, between the successive impression cylinders which are capable of receiving and transmitting the sheets to and from the several impression cylinders whether the latter are in or out of contact with the form members.

It consists further, in a new and improved arrangement of sheet carrying devices on the impression and transfer cylinders, whereby the said sheet carrying devices, such as grippers, are operated in harmony with the rotation of the several cylinders and are capable of seizing and releasing the sheets whether or not the impression is tripped.

Other objects and features of construction will appear as the specification proceeds.

The invention is embodied in a concrete structure in the accompanying drawings, in which is shown the preferred form; the invention, however, is susceptible of wide modifications without departing from the true spirit and scope thereof.

In the said drawings: Figure 1 is a side elevation of so much of a printing machine as is necessary to properly illustrate my invention. Fig. 1^a is a detail view showing a part of the feed board and the gages used in connection therewith. Fig. 2 is a horizontal transverse sectional plan view on the line 2—2 of Fig. 1. Fig. 3 is a view partly in section, on the line 3—3 of Fig. 2, looking in the direction of the arrow. Fig. 4 is a detail view, partly in section, and with parts removed looking in the direction of the arrow 4 in Fig. 3.

Similar characters of reference indicate corresponding parts in the several views.

1 indicates a framework of any suitable construction for properly supporting the parts comprising the machine. In this framework are mounted a plurality of printing couples, preferably of a rotary nature, there being in the present instance three such couples, arranged substantially one above the other. Each couple consists of a

form and impression member, and is adapted to make a number of revolutions to each impression. In the present instance, the cylinders revolve twice to each impression.

2 is the impression cylinder, and 3 the form cylinder of the first printing couple, while 4 is the impression cylinder and 5 the form cylinder of the second printing couple, and 6 is the impression cylinder and 7 the form cylinder of the third printing couple.

The impression and form cylinders are preferably of equal diameter, as are the transfer cylinders 8, 9 and 10, which are interposed respectively between the first and second impression cylinder, between the second and third impression cylinder, and between the third impression cylinder and a suitable delivery mechanism (not shown).

This last mentioned cylinder 10 may be a collecting cylinder, if desired. All of the impression and transfer cylinders, except the first impression cylinder, are provided with grippers closed by springs in the usual way, and opened by means of cams. The first impression cylinder, however, is provided with tumbling grippers which are caused to tumble back and forth nearly one-half of a revolution by suitable means which will be more fully hereinafter described.

In multi-couple multi-revolution machines, this construction in which the first impression cylinder is provided with tumbling grippers is advantageous for the reason that the sheet must be positively seized and that the feed board might interfere with the operation of spring seated grippers which have to be raised above the surface of the cylinder when the feeding point is reached.

It is furthermore advantageous in this type of machine that the first impression cylinder should print and deliver the sheet during its first revolution, remaining idle during its second or further revolutions, as otherwise the sheet would have to be carried a second or third time past the feeding point. The other impression cylinders, however, are so arranged with relation to their respective form and transfer cylinders, that the impression takes place during their first revolution while the sheet is delivered during a portion of the second revolution of the cylinders.

11 is the feed board, adjacent to which are gages 12, against which the sheets are fed, and which are raised in a well known manner when the grippers on the cylinder 2 seize a sheet.

13 indicates inking mechanism of a suitable construction used in connection with each plate cylinder.

All of the cylinders are geared together, being driven from the driving pinion 14 which latter also transmits motion through the intermediate gear 15 and pinion 16 to the gear 17 mounted on the cam shaft 18.

The cylinder 2 is provided with the grippers 19 which are arranged to tumble backward and forward nearly half a revolution by means of a crosshead 20 mounted on the 5 gripper shaft 21. Suitable means are provided for closing and opening the grippers once to a number of revolutions of the cylinder, and during the first revolution of the cylinder only. These means, in the present 10 instance, take the form of two rotating cams 22 and 23, which are driven so as to rotate once to a number of revolutions of the impression cylinder by means of the pinion 24 and gear 25 (the relation being one to two), 15 and suitable connections as the levers 26 and 27, operated by the said cams, so that the pins 28 carried by the said levers will project into the plane of the rotating crosshead of the cylinder, the lever 26 acting to close the grippers, and the lever 27 to open the grippers. The parts are so arranged that as the grippers come to the feeding point, the lever 26 will cause the grippers to be closed, so as to seize a sheet, which latter then receives an 25 impression when it reaches the form cylinder 3. During the same revolution, and when the grippers reach the axial line between the cylinders 2 and 8, the grippers are opened by the lever 27, whereby the sheet is released 30 and taken on the transfer cylinder 8. The cylinder 2 then completes its revolution, and makes another revolution, with the grippers in their open position, running idly without taking another sheet. The grippers on the 35 other impression cylinders are closed by springs in the usual way, and opened by cams to receive a sheet during one revolution, and opened to deliver the sheet during another (the succeeding) revolution. The 40 transfer cylinders 8 and 9 are provided with grippers similar to the ones on the impression cylinders 4 and 6. These grippers, however, are opened and closed twice during the first revolution, and are preferably idle 45 during the second revolution. Any suitable means may of course be employed for effecting this, but preferably I employ rocking cams which are adapted to be moved into the plane or path of the usual rollers on 50 cranks (or any other means) carried by the gripper shafts, at predetermined intervals. The preferred construction of these parts is as follows: The first transfer cylinder 8 is provided with the spring-seated grippers 29 55 connected to which is the roll 30 adapted to be acted upon during the first revolution of the cylinder by the cam 31. This cam is shown in the present instance as a stationary cam for the reason that there is no sheet on 60 the first impression cylinder during the second revolution and it is therefore not necessary to move this cam out of the plane of the gripper mechanism during the second revolution. This cam will therefore also 65 open the grippers during the second revolu-

tion, but there being no sheet on the first impression cylinder, no result will follow. The cam 32, however, which acts to open the grippers to deliver the sheet to the second impression cylinder is moved into the plane 70 of the gripper mechanism during the first revolution, and out of the plane of the gripper mechanism during the second revolution, so that the said grippers will not pierce the sheet on the second impression cylinder 75 which is carried past the axial line between the first transfer cylinder and second impression cylinder and delivered during the second revolution of the said second impression cylinder. To this end the cam 32 is 80 mounted on the rocking lever 33 pivoted at 34 and having a roll 34^a at its outer end engaging with the cam 35. This cam 35 is mounted on the shaft 36 conveniently driven from the shaft 37 of the second impression 85 cylinder by means of the pinion 38 and gear 39. This cam shaft makes, in the present instance, one revolution to every two revolutions of the printing and transfer cylinders. This cam shaft also controls the cam 90 40 mounted on the lever 41 pivoted at 42 and having the friction roll 43 at its outer end, which engages the cam 44 mounted on the said cam shaft. This cam 41 is adapted to be moved into the plane of the spring 95 seated gripper mechanism 45 on the second impression cylinder during its first revolution so as to open the grippers to receive the sheet and substantially at the same moment the gripper mechanism on the first transfer 100 cylinder is opened to deliver the sheet.

The rocking cam 46 which is mounted on the lever 47 pivoted at 48 is adapted to open the gripper mechanism during the second revolution of the second impression cylinder. In a similar manner, the cam 49 on the second transfer cylinder is mounted on the lever 50 pivoted at 51 and is adapted to open the gripper mechanism 52 on the second transfer cylinder during its first revolution 110 and substantially at the same moment the gripper mechanism on the second impression cylinder is opened by the cam 46.

The cam 53 is mounted on the lever 54 pivoted at 55 and is adapted to open the 115 gripper mechanism on the second transfer cylinder during its first revolution only. Preferably the cams 46, 49 and 53 are actuated from the same rotating cam 56 mounted on the cam shaft 57 which is caused 120 to rotate in the present instance once to every two revolutions of the cylinder by means of the pinion 58 and gear 59. To this end the lever 50 is provided with a friction roll 60 in engagement with the said cam 56 125 and further carries a gear sector 61 which imparts its motion to an intermediate pinion 62 mounted in the framework of the machine, and which latter, in turn, is in engagement with a similar gear segment 63 on the 130

end of the lever 47. By this means, it will be seen that the two rocking levers 47 and 50 will be moved toward the circumference of their respective cylinders simultaneously so as to open the gripper mechanism in the proper manner. The lever 54 of the cam 53 is provided with a roll 64 which engages with the cam 56.

The last impression cylinder, which in this instance is the third impression cylinder, preferably does not deliver its sheet directly to its transfer cylinder, but delivers it to a suitable guide 65 interposed between the said impression and transfer cylinders, so that the sheet may be carried on to be delivered with its printed side out. It is obvious, further, that the transfer cylinder 10 may be a collecting cylinder, and from this transfer cylinder the sheet may be delivered in any suitable way as by a drop delivery or otherwise. This is fully disclosed in an application filed by me on the 11th day of August, 1902, Ser. No. 119,212, and it is therefore thought unnecessary to enter into the details of this part of the machine in the present application.

The third impression cylinder is provided with a spring-seated gripper mechanism 66 and with throw-off fingers 67 of a well known construction. Inasmuch as the delivery point of this cylinder is but a short distance away from the receiving point or from the axial line between the second transfer cylinder and the third impression cylinder, only one cam is necessary in this instance, to open the gripper mechanism on this third impression cylinder. This cam which is designated by the numeral 68, is adapted to open the gripper mechanism during the first revolution of the cylinder to receive a sheet and again to open the gripper mechanism during its second revolution to deliver the sheet, the said cam being moved into different positions to effect this operation. In other words, the cam is in the plane of the gripper mechanism during every revolution of the cylinder, but opens the grippers at a different point of the rotation of the cylinder. The precise means for carrying out this, may of course be varied, but preferably this cam is caused to oscillate around the shaft of the cylinder by being provided with a sleeve 69 which at its outer end is provided with a gear segment 70 adapted to be operated by any suitable means to shift the cam back and forth a certain distance from the receiving point to the delivery point of the cylinder. Preferably this cam is also operated from the rotating cam 56 by means of the gear sector 71 pivoted at 72 and provided with an arm 73 having a friction roll 74 which engages with the said cam 56. It will thus be seen that the cam 56 controls the gripper cams on the second transfer cylinder and third impres-

sion cylinder as well as one of the cams of the second impression cylinder.

Each of the three impression cylinders is mounted in an eccentric bushing 75 upon its shaft, whereby when the said eccentric bushings are turned, the impression cylinders will be moved in and out of printing contact with the plate cylinders. The distance which it is necessary to raise these impression cylinders in order to properly trip the same, is only about three-sixteenths of an inch, so that the gears on the respective cylinders are never out of mesh with each other. This tripping of the impression cylinders does not affect their relation to the transfer cylinders, for the sheet is always capable of being passed through the machine whether or not the impression is tripped. The said eccentric bushings 75 are connected by means of the short arms 76, connecting rod 77, and levers 78, to the rockshafts 79, 80 and 81, there being provided one rockshaft for each impression cylinder. Suitable means are provided for rocking these rockshafts at regular intervals so as to automatically trip and untrip the impression cylinders at predetermined intervals once to each cycle of the machine. In the present instance, the impression cylinders are tripped during their second revolution of each cycle of the machine. Obviously, the means for accomplishing this may be varied widely, but preferably there is mounted upon the cam shaft 18 three cams 82, 83 and 84, which, as previously explained, are given one revolution to a number of revolutions (in the present instance to every two revolutions) of the machine.

85 is a shaft extending transversely of the machine and on which are loosely mounted a plurality of arms (in the present instance three), one for each impression cylinder, numbered respectively 86, 87 and 88. Each of the said arms is provided with a roller 89, which engages in its respective cam groove on one of the cams 82, 83 and 84.

Suitable means are provided for communicating the motion of the arms 86, 87 and 88 to the rockshafts 79, 80 and 81. In the present instance, these means take the form of slotted connections 90, 91 and 92, connected, by means of the levers 93, to the rockshafts aforesaid, and receiving the motion of the arms aforesaid by means of pins 94 carried at the lower ends of the said arms, and adapted to play in the slots 95 of the connections aforesaid and to be locked with the said connections when the pins 94 are in the recess 96 of the said slots. From this it will be understood that during the normal operation of the machine, the cams 82, 83 and 84, by their rotation, will cause the arms 86, 87 and 88 to oscillate, thereby moving the slotted connections aforesaid and rocking the rockshafts. This causes the

130

impression cylinders to be moved alternately into and out of contact with the form members. Interrupting means are provided, however, for lifting the slotted connections so as to cause the pins 96 to play idly in the slots 95, whereby the form and impression members will be maintained separated as long as the slotted connection is held in its elevated position. The means for effecting this may of course take many forms, but, in the present instance, there is provided a plurality of rocking cams 97, 98 and 99. These cams are mounted slidably upon the shaft 100, and are provided with the pins 101 extending in under the slotted connections aforesaid, so that when they are moved into the plane of the pins 102 which are conveniently mounted on the cams 82, 83 and 84, the said pins 102 will come in contact with the cam portion 103 of the said cams, thereby turning the same around the shaft 100, and lifting the slotted connection up, so that the pins 96 will play idly in the slots 95. The parts should of course be so arranged that these several cams 97, 98 and 99 can be actuated from a single actuating device, and connections should be made whereby the cam 98 will not lift the slotted connection 95 until the succeeding cycle of the machine or after two revolutions have taken place, and so on, in order that the sheet properly printed by the first printing couple, may be allowed to pass through the machine and be printed by the remaining couples before the automatic tripping mechanism is rendered incapable of returning the members of the printing couple into printing contact. The means for effecting this may take many forms, but, in the present instance, there is provided a treadle 104 which, when it is depressed, will, through suitable connections, move the member 105 so as to cause the latter, by means of its bifurcated end 106, to move the rocking cam 97 and sliding cam 99 into the plane of the pin 102. This may be effected by various mechanical contrivances, but, in the present form, there is shown a swinging lever 107 pivoted at its central portion 108, and having a forked end 109 which is in engagement with the member 105, and which, when turned, would cause the said member to be moved inward against the pressure of the spring 110. The lever 107 is suitably connected to the foot treadle as by means of the bell crank 111 and treadle rod 112. When the pin 102 now comes in contact with the cam portion 103, the slotted connection 90 will be raised, thereby causing the pin 96 to play idly in the slot 95, and preventing the members of the first printing couple from returning into printing contact.

Resting upon the end of the slotted connection is a lever 113 pivoted as at 114 on a suitable bracket in the framework and con-

nected to the bell crank 115 by means of the link 116, so that when the said slotted connection is raised, the said bell crank 115 will, through its forked end 117, compress the spring 118 which bears against the cam 98, thereby causing the said cam to be moved into the plane of the pin 102 on the cam 83, so that on the succeeding cycle the slotted connection 91 will be lifted thereby maintaining the members of the second printing couple in their separated position. In like manner, the raising of the slotted connection 91 will lift the second lever 113, resting upon its outer end, and will, through similar devices, as previously described, communicate the motion to the cam 99, and in this way the members of the third printing couple will be kept in their separated position upon the next succeeding cycle of the machine.

The lifting of the slotted connection 90 will immediately act to compress the spring 118 and to move the cam 98 into the path of the pin on the cam 83. In order, however, to maintain this spring 118 compressed when the operator releases the treadle, a suitable latch is provided which prevents the return of this spring, and which acts automatically to release it after the connection 91 has been raised. This latch mechanism takes the form of a lever 119 which, by reason of the spring 120, is forced in behind the bell crank 117. This lever 119 as well as the spring 120 are both connected to a bushing 121 which is mounted loosely on the shaft 122. This latch is automatically released by the pin 123 on the cam 82 which comes in contact with the lever 124 also connected to the said bushing 121, thereby allowing the spring 118 to expand. On the other side of the cam 98, there is another spring 125 which is of sufficient strength to move the said cam 98 back and out of the plane of the pin 102 when the spring 118 is not compressed. It will be noticed that a similar latch 126 is provided for the spring 127 operating against the cam 99 and released by the pin 123 on the cam 83, the said cam 99 being returned to its original position when pressure is released upon the spring 127 by means of the spring 128. In this way the several couples of the printing machine will have their tripped position prolonged in regular sequence during successive cycles of the machine and brought under the influence of the automatic tripping and untripping means also in regular sequence during successive cycles of the machine. If it is desired to maintain the members of the various printing couples in their separated positions during a number of cycles of the machine, then the treadle 104 is locked in its depressed position as by means of the pin 129 which travels in a vertical slot 130 and is then turned by twisting the

foot around into the horizontal slot 131. In this manner it will be understood that although the automatic latch mechanisms will be automatically released once to each cycle of the machine, they will have no effect upon the caps 98 and 99, because the slotted connections are kept in their raised position and the springs 118 and 127 are therefore prevented from returning to their expanded position. When the foot treadle is now released or unlocked, the counter-weight 132 will move the lever 107 outward and the spring 110 will move the member 105 outward, also, thereby positively sliding the cam 97 out of the plane of the pin 102 by reason of the forked connection 106 which rests in the circumferential groove 133 of the bushing of the said cam 97. The automatic tripping and untripping means now regaining control of the first printing couple, will, in turn, act to release the latch mechanism of the second printing couple, and that in turn will release the latch mechanism for the third printing couple, and thus the machine will be restored to its normal function again.

The operation of the machine, as well as the structure thereof, is thought to have been fully disclosed in the foregoing description, and accordingly will not be repeated here.

What is claimed is:

1. In a multi-couple multi-revolution printing machine, the couples of which are adapted to print on the same side of the sheet, the combination with a first impression cylinder adapted to receive, print and release a sheet during the first revolution of its cycle, and to rotate idly during the remainder of its cycle, of a second impression cylinder adapted to receive and print the sheet during the first revolution of its cycle and to release the same after the said first revolution, means for transferring the sheets from one impression cylinder to another, and form members adapted to co-act with the impression members.

2. In a multi-couple two-revolution printing machine, the couples of which are adapted to print on the same side of the sheet, the combination with a first impression cylinder adapted to receive, print and release a sheet during its first revolution and to rotate idly during its second revolution, of a second impression cylinder adapted to receive and print the sheet during its first revolution and to release the sheet during its second revolution, means for transferring the sheet from one impression cylinder to another, and form members adapted to co-act with the impression members.

3. In a multi-couple multi-revolution printing machine, the couples of which are adapted to print on the same side of the sheet, the combination of a first impression

cylinder adapted to receive, print and release a sheet during the first revolution of its cycle, and to rotate idly during the remainder of its cycle, a second impression cylinder adapted to receive and print the sheet during the first revolution of its cycle and to release the same after the said first revolution, a transfer cylinder adapted to transfer the sheet from one impression cylinder to the other during its first revolution only, and to rotate idly during the remainder of its cycle, and form members adapted to co-act with the impression members.

4. In a multi-couple two-revolution printing machine, the couples of which are adapted to print on the same side of the sheet, the combination of a first impression cylinder adapted to receive, print and release a sheet during its first revolution and to rotate idly during its second revolution, a second impression cylinder adapted to receive and print the sheet during its first revolution and to release the same during its second revolution, a transfer cylinder adapted to transfer the sheet from the first to the second impression cylinder during its first revolution and to rotate idly during its second revolution.

5. In a multi-couple multi-revolution printing machine, the couples of which are adapted to print on the same side of the sheet, the combination of a plurality of impression cylinders adapted to receive and print a sheet during the first revolution of their cycle and to release the sheet after their first revolution, a first impression cylinder adapted to receive, print and release the sheet during the first revolution of its cycle and to rotate idly during the remainder of its cycle, means for transferring the sheet from one impression cylinder to another, and form members adapted to co-act with the impression members.

6. In a multi-couple two-revolution printing machine, the couples of which are adapted to print on the same side of the sheet, the combination of a plurality of impression cylinders adapted to receive and print a sheet during their first revolution and to release the sheet during their second revolution, a first impression cylinder adapted to receive, print and release the sheet during its first revolution and to rotate idly during its second revolution, means for transferring the sheet from one impression cylinder to another, and form members adapted to co-act with the impression members.

7. In a multi-couple multi-revolution printing machine, the couples of which are adapted to print on the same side of the sheet, the combination of a plurality of impression cylinders adapted to receive and print a sheet during the first revolution of

their cycle, and to release the sheet after their first revolution, a first impression cylinder adapted to receive, print and release the sheet during the first revolution of its 5 cycle and to rotate idly during the remainder of its cycle, transfer cylinders adapted to transfer the sheet from one impression cylinder to another during their first revolution and to rotate idly during the remainder 10 of their cycle, and form members adapted to co-act with the impression members.

8. In a multi-couple two-revolution printing machine, the couples of which are adapted to print on the same side of the sheet, 15 the combination of a plurality of impression cylinders adapted to receive and print a sheet during their first revolution and to release the sheet during their second revolution, a first impression cylinder adapted to receive, print and release the sheet during its 20 first revolution and to rotate idly during its second revolution, transfer cylinders adapted to transfer the sheet from one impression cylinder to another during their first revolution, and to rotate idly during their second revolution, and form members adapted to co-act with the impression members.

9. In a printing machine, the combination with the impression cylinders of a plurality 30 of multi-revolution couples adapted to print on the same side of the sheet, and multi-revolution transfer cylinders, of grippers on the first impression cylinder, means for closing and opening the grippers on the 35 said first impression cylinders during the first revolution of its cycle only to receive and release the sheet, the said cylinder rotating idly during the remainder of its cycle, grippers on the other impression cylinder or 40 cylinders, means for opening the said grippers to receive the sheet during the first revolution of its or their cycle, means for opening the grippers to release the sheet after the first revolution of the said other cylinder 45 or cylinders, grippers on the transfer cylinders, and means for opening the said grippers twice during the first revolution of their cycle to receive and release the sheet.

10. In a printing machine, the combination 50 with the impression cylinders of a plurality of two-revolution couples adapted to print on the same side of the sheet, and two-revolution transfer cylinders, of grippers on the first impression cylinder, means for closing and opening the grippers on the said 55 first impression cylinder during its first revolution to receive and release the sheet, the said cylinder rotating idly during its second revolution, grippers on the other impression 60 cylinder or cylinders, means for opening the said grippers to receive the sheet during its or their first revolution, means for opening the grippers to release the sheet during the second revolution of the said other cylinder

or cylinders, grippers on the transfer cylinders, and means for opening the said grippers twice during their first revolution to receive and release the sheet.

11. In a printing machine, the combination 65 of two impression cylinders and a transfer cylinder adapted to transfer sheets from one impression cylinder to the other, of grippers on the said cylinders, a plurality of rocking cams for opening the said grippers, and a rotating cam adapted to actuate the 70 said rocking cams.

12. In a printing machine, the combination 75 of two cylinders, grippers thereon, two independently mounted rocking cams, one for the grippers on each cylinder, means for 80 rocking one of said cams, and means for rocking the other of said cams from the first one.

13. In a printing machine, the combination 85 of two cylinders, grippers thereon, two independently mounted rocking cams, one for the grippers on each cylinder, means for rocking one of said cams to open the grippers on one cylinder, and means for rocking the other of said cams from the first 90 one to open the grippers on the other cylinders whereby the sheet is transferred from cylinder to cylinder.

14. In a printing machine, the combination 95 of two cylinders, grippers thereon, two rocking cams, one for the grippers on each cylinder, means for rocking one of said cams, racks carried by both cams, and an intermediate pinion in mesh with both 100 racks.

15. In a printing machine, the combination 105 with a plurality of multi-revolution printing couples composed of form and impression members adapted to print on the same side of the sheet, automatic means for each printing couple for periodically moving the members of said couple out of and into contact with each other once to each cycle of the machine, interrupting means for preventing the automatic means of the first 11 printing couple from returning the members thereof into contact, locking means operated automatically when the interrupting means is actuated for so maintaining the parts, and connections between the automatic 115 means of the first couple and the interrupting means of the second couple whereby each automatic means is prevented sequentially from returning the members of the said couples into contact and for so maintaining 120 them as long as the locking means is effective.

16. In a printing machine, the combination 125 with a plurality of multi-revolution printing couples composed of form and impression members adapted to print on the same side of the sheet, automatic means for each printing couple for periodically moving

- the members of said couple out of and into contact with each other once to each cycle of the machine, interrupting means for preventing the automatic means of the first printing couple from returning the members thereof into contact, locking means operating automatically upon actuation of the interrupting means of the first couple for so maintaining the parts, and connections between the automatic means of the first couple and the interrupting means of the second couple whereby the automatic means of the second couple is prevented sequentially from returning the members of the said couple into contact and for so maintaining them as long as the locking means is effective, and whereby when the locking means is released, the several couples are sequentially brought under the control of their respective automatic means.
17. In a printing machine, the combination with two multi-revolution printing couples composed of form and impression members, a plurality of rockshafts, one for each printing couple, connections between the rockshafts and one of the members of each printing couple for moving the said members into and out of contact, a plurality of rotating cams, one for each printing couple, connections for operating the rockshafts adapted to be actuated by the rotating cams, a plurality of rocking cams adapted to render the connections for operating the rockshafts inoperative, means for rocking the said cams, an actuating device for moving the rocking cam of the first printing couple into the plane of the means for rocking the same, intermediate means between the connections for operating the rockshaft of the first printing couple and the rocking cam of the second printing couple for moving the said rocking cam upon the next cycle of the machine into the plane of the means for rocking the same when the connection for operating the rockshaft of the first printing couple is rendered inoperative, a latch mechanism to prevent the return of the rocking cam of the second printing couple, and means, controlled by the first printing couple for releasing the said latch after one cycle of the machine.
19. In a printing machine, the combination with a plurality of multi-revolution printing couples composed of form and impression members, a plurality of rockshafts, one for each printing couple, connections between the rockshafts and one of the members of each printing couple for moving the said members into and out of contact, a plurality of rotating cams, one for each printing couple, connections for operating the rockshafts adapted to be actuated by the rotating cams, a plurality of rocking cams adapted to render the connections for operating the rockshafts inoperative, means for rocking the said cams, an actuating device for moving the rocking cam of the first printing couple into the plane of the means for rocking the same, intermediate means for moving the rocking cams of each couple except the first one into the plane of its respective means for rocking the same controlled by the connection for operating the rockshaft of its preceding couple when the said connection is rendered inoperative, a latch mechanism adapted to prevent the return of the rocking cams of all the couples except the first one, and means for releasing the latch mechanism of each couple controlled by its preceding couple.
20. In a printing machine, the combination with a plurality of multi-revolution printing couples composed of form and impression members, a plurality of rockshafts, one for each printing couple, connections between the rockshafts and one of the members of each printing couple for moving the said members into and out of contact, a plurality of rotating cams, one for each printing couple, connections for operating the rockshafts adapted to be actuated by the rotating cams, a plurality of rocking cams adapted to render the connections for operating the rockshafts inoperative, means for rocking the said cams, an actuating device for moving the rocking cam of the first printing couple into the plane of the means for rocking the same, intermediate means for moving the rocking cams of each couple except the first one sequentially into the plane of the means for rocking the same controlled by the connection for operating the rockshaft of its preceding couple when the said connection is rendered inoperative, a latch mechanism adapted to prevent the return of the rocking cams of all the couples except the first one, and means for releasing the latch mechanism of each couple controlled by its preceding couple.
18. In a printing machine, the combination with two multi-revolution printing couples composed of form and impression members, a plurality of rockshafts, one for each printing couple, connections between the rockshafts and one of the members of each printing couple for moving the said members into and out of contact, a plurality of rotating cams, one for each printing couple, connections for operating the rockshafts adapted to be actuated by the rotating cams, a plurality of rocking cams adapted to render the connections for operating the rockshafts inoperative, means for rocking the said cams, an actuating device for moving the rocking cam of the first printing couple into the plane of the means for rocking the same, intermediate means for moving the rocking cams of each couple except the first one sequentially into the plane of the means for rocking the same controlled by the connection for operating the rockshaft of its preceding couple when the said connection is rendered inoperative, a latch mechanism adapted to prevent the return of the rocking cams of all the couples except the first one, and means for releasing the latch mechanism of each couple controlled by its preceding couple.

plane of its respective means for rocking the same controlled by the connections for operating the rockshaft of its preceding couple when the said connection is rendered 5 inoperative, latch mechanism adapted to prevent the return of the rocking cams of each printing couple except the first one, and means for sequentially releasing the said latch mechanism of the several couples after 10 one cycle of the machine controlled by its preceding couple.

21. In a printing machine, the combination with two multi-revolution printing couples composed of form and impression members, a plurality of rockshafts, one for each printing couple, connections between the rockshafts and one of the members of each printing couple for moving the said members into and out of contact, a cam shaft extending transversely of the machine, a plurality of rotating cams mounted thereon, one for each printing couple, connections for operating the rockshafts adapted to be actuated by the rotating cams, an auxiliary cam shaft extending transversely of the machine, a plurality of rocking cams slidably mounted on said shaft adapted to render the connections for operating the rockshafts inoperative, means carried by the rotating cams 25 for rocking the rocking cams, a spring-seated actuating device for moving the rocking cam of the first printing couple into and out of the plane of the means for rocking the same on the rotating cam, a spring on the auxiliary cam shaft abutting against the rocking cam of the second printing couple, intermediate means between the connection for operating the rockshaft of the first printing couple and the spring abutting against the other side of the said rocking cam of the second printing couple for moving the said rocking cam into the plane of its means for rocking it.

22. In a printing machine, the combination with a plurality of multi-revolution printing couples composed of form and impression members, a plurality of rockshafts, one for each printing couple, connections between the rockshafts and one of the members of each printing couple for moving the said members into and out of contact, a cam shaft extending transversely of the machine, a plurality of rotating cams mounted thereon, one for each printing couple, connections for operating the rockshafts adapted to be actuated by the rotating cams, an auxiliary cam shaft extending transversely of the machine, a plurality of rocking cams slidably mounted on said shaft adapted to render the connections for operating the rockshafts inoperative, means carried by the rotating cams for rocking the rocking cams, a spring-seated actuating device for moving the rocking cam of the first printing couple into and out of the plane of the means for rocking the same on the rotating cam, a spring on the auxiliary cam shaft abutting against the rocking cam of the second printing couple, intermediate means between the connection for operating the rockshaft of the first printing couple and the spring abutting against the other side of the said rocking cam of the second printing couple for moving the said rocking cam into the plane of its means for rocking it.

23. In a printing machine, the combination with a plurality of multi-revolution printing couples composed of form and impression members, a plurality of rockshafts, one for each printing couple, connections between the rockshafts and one of the members of each printing couple for moving the said members into and out of contact, a cam shaft extending transversely of the machine, a plurality of rotating cams, 5 one for each printing couple, connections for operating the rockshafts adapted to be actuated by the rotating cams, an auxiliary cam shaft extending transversely of the machine, a plurality of rocking cams slidably mounted on said shaft adapted to render the connections for operating the rockshafts inoperative, means carried by the rotating cams for rocking the rocking cams, a spring-seated actuating device for moving the rocking cam of the first printing couple into and out of the plane of the means for rocking the same on the rotating cam, springs on the auxiliary cam shafts abutting against the rocking cams of all the printing couples except the first one, intermediate means for moving the rocking cams of each couple except the first one into the plane of its respective means for rocking 10

printing couple, mounted on said cam shaft, connections for operating the rockshafts adapted to be actuated by the rotating cams, an auxiliary cam shaft extending transversely of the machine, a plurality of rocking cams mounted slidably thereon and adapted to render the connections for operating the rockshafts inoperative, means carried by the rotating cams for rocking the said rocking cams, a spring-seated actuating device for moving the rocking cam of the first printing couple into and out of the plane of the means for rocking the same on the rotating cam, a spring on the auxiliary cam shaft abutting against the rocking cam of the second printing couple, intermediate means between the connection for operating the rockshaft of the first printing couple and the spring abutting against the rocking cam of the second couple for moving the said second rocking cam upon the next cycle of the machine into the plane of its means for rocking it mounted on the rotating cam of the second printing couple when the connection for operating the rockshaft of the first printing couple is rendered inoperative, a latch mechanism adapted to prevent the return of the spring and rocking cam of the second printing couple, means mounted on the rotating cam of the first printing couple for releasing the said latch after one cycle of the machine, and a spring abutting against the other side of the said rocking cam of the second printing couple for moving the said rocking cam out of the plane of the means for rocking it.

24. In a printing machine, the combination with a plurality of multi-revolution printing couples composed of form and impression members, a plurality of rockshafts, one for each printing couple, connections between the rockshafts and one of the members of each printing couple for moving the said members into and out of contact, a cam shaft extending transversely of the machine, a plurality of rotating cams mounted thereon, one for each printing couple, connections for operating the rockshafts adapted to be actuated by the rotating cams, an auxiliary cam shaft extending transversely of the machine, a plurality of rocking cams slidably mounted on said shaft adapted to render the connections for operating the rockshafts inoperative, means carried by the rotating cams for rocking the rocking cams, a spring-seated actuating device for moving the rocking cam of the first printing couple into and out of the plane of the means for rocking the same on the rotating cam, springs on the auxiliary cam shafts abutting against the rocking cams of all the printing couples except the first one, intermediate means for moving the rocking cams of each couple except the first one into the plane of its respective means for rocking 15

- the same carried by the rotating cams and controlled by the connection for operating the rockshaft of its preceding couple when the said connection is rendered inoperative, 5 latch mechanism adapted to prevent the return of the springs and rocking cams of all the couples except the first one, means for releasing the latch mechanism of each couple mounted on the rotating cam of its preceding couple, and springs abutting against the other side of the said rocking cams except the first one for moving the said rocking cams out of the plane of the means for rocking them.
- 10 24. In a printing machine, the combination with a plurality of multi-revolution printing couples composed of form and impression members, a plurality of rockshafts, one for each printing couple, connections between the rockshafts and one of the members of each printing couple for moving the said members into and out of contact, a cam shaft extending transversely of the machine, a plurality of rotating cams mounted thereon, one for each printing couple, connections for operating the rockshafts adapted to be actuated by the rotating cams, an auxiliary cam shaft extending transversely of the machine, a plurality of rocking cams 25 30 35 40 45 50 55 60 65 70 75 80 85 90 95 100 105 110 115 120 125 130 135 140 145 150 155 160 165 170 175 180 185 190 195 200 205 210 215 220 225 230 235 240 each printing couple for periodically moving the members of said couple into and out of contact with each other, interrupting means for preventing the automatic means of the first printing couple from returning the members thereof into contact, locking means operating automatically upon actuation of the interrupting means aforesaid for so maintaining the parts, and connections between the automatic means of one couple and the interrupting means of the next adjacent couple whereby each automatic means is prevented sequentially during successive cycles of the machine from returning the members of the said couples into printing contact and for so maintaining them as long as the locking means is effective.

29. In a printing machine the combination with a plurality of multi-revolution printing couples composed of form and impression members adapted to print on the same side of the sheet, automatic means for each printing couple for periodically moving the members of said couple into and out of contact with each other, interrupting means for preventing the automatic means of the first printing couple from returning the members thereof into contact, locking means operating automatically upon actuation of the interrupting means aforesaid for so maintaining the parts, and connections between the automatic means of one couple and the interrupting means of the next adjacent couple whereby each automatic means is prevented sequentially during successive cycles of the machine from returning the members of the said couples into printing contact and for so maintaining them as long as the locking means is effective, and whereby, when the locking means is released, the several couples are sequentially during successive cycles of the machine brought under the control of their respective automatic means.

30. In a printing machine, the combination with the form and impression members of a plurality of multirevolution printing couples, of automatic tripping and untripping means for each couple, interrupting means for the automatic tripping and untripping means of each couple normally inoperative, an actuating device for positioning the interrupting means of the first printing couple to interrupt the normal operation of the automatic tripping and untripping means of the said first couple, and connections between the automatic tripping and untripping means of the first couple and the interrupting means of the second couple for positioning the said interrupting means of the said second couple to sequentially interrupt the normal operation of the automatic tripping and untripping means of the said second couple when the normal operation of the automatic tripping and untripping means of the said second couple

means of the first couple has been interrupted.

31. In a printing machine, the combination with the form and impression members of a plurality of multirevolution printing couples, of automatic tripping and untripping means for each couple, interrupting means for the automatic tripping and untripping means of each couple normally inoperative, an actuating device for positioning the interrupting means of the first printing couple to interrupt the normal operation of the automatic tripping and untripping means of the said first couple, and connections between the automatic tripping and untripping means of the first couple and the interrupting means of the second couple for positioning the said interrupting means of the said second couple to sequentially interrupt the normal operation of the automatic tripping and untripping means of the said second couple when the normal operation of the automatic tripping and untripping means of the first couple has been interrupted, and to act sequentially to allow the automatic tripping and untripping means aforesaid to regain control of the members of the printing couples.

32. In a printing machine, the combination with the form and impression members of a plurality of multirevolution printing couples, of automatic tripping and untripping means for each couple, interrupting means for the automatic tripping and untripping means of each couple normally inoperative, an actuating device for positioning the interrupting means of the first printing couple to interrupt the normal operation of the automatic tripping and untripping means of the said first couple, and connections between the automatic tripping and untripping means of the first couple and the interrupting means of the second couple for positioning the said interrupting means of the said second couple to sequentially interrupt the normal operation of the automatic tripping and untripping means of the said second couple when the normal operation of the automatic tripping and untripping means of the first couple has been interrupted, and upon the succeeding cycle of the first printing couple to act sequentially to allow the automatic tripping and untripping means aforesaid to regain control of the members of the printing couples.

33. In a printing machine adapted to print two or more impressions on the same side of a sheet, the combination of the form and impression members of a first printing couple, automatic means for normally placing said members into and out of printing contact during the same cycle of the machine, the form and impression members of a second printing couple, automatic means independent from the said first automatic

means for normally placing the members of the second printing couple into and out of printing contact during the same cycle of the machine, an actuating device for interrupting the operation of the first automatic means to keep the members of the second printing couple out of printing contact during successive cycles.

Signed at New York city this 15th day of November 1905.
